CLAIM

The ornamental design for a 3 port heating, ventilation and air conditioning manifold as shown and described.

DESCRIPTION

The file of this patent contains at least one drawing executed in color. Copies of this patent with color drawing(s) will be provided by the Office upon request and payment of the necessary fee.

FIG. 1 is a front elevation view of a 3 port heating, ventilation and air conditioning manifold showing our new design.

FIG. 2 is a top plan view thereof.

FIG. 3 is a bottom plan view thereof.

FIG. 4 is a right side elevation view thereof.

FIG. 5 is a left side elevation view thereof.

FIG. 6 is a left-front perspective view thereof.

FIG. 7 is a left-rear perspective view thereof.

FIG. 8 is a rear elevation view thereof.

FIG. 9 is a rear elevation view thereof with the support hook extended; and,

FIG. 10 is a left side elevation view thereof with the support hook extended.
